UNITED STATES PATENT OFFICE.

WILLIAM J. STEENROD, OF BENTON HARBOR, MICHIGAN, ASSIGNOR TO BAKER-VAWTER COMPANY, OF BENTON HARBOR, MICHIGAN, A CORPORATION OF MICHIGAN.

LOOSE-LEAF BINDER.

Application filed October 24, 1925. Serial No. 64,490.

In the manufacture of heavy loose leaf binders for bookkeeping and like purposes, the sides of the binder are ordinarily hinged to what are usually termed post bars, to one which the posts which engage the orificed sheets are secured and the other one of which is orificed and equipped with a locking mechanism arranged to engage the posts. My present invention relates to post bars formed of sheet metal, and my invention relates to the construction of the bar itself and also to the novel locking mechanism with which it is equipped, and has for its object the provision of a strong, simple binder bar which may be conveniently and economically manufactured and novel and efficient locking mechanism of simple construction and few parts which shall render the bar highly useful and desirable to serve the purposes for which it was designed. With these ends in view I have designed and invented the novel post bar mechanism hereinafter described and illustrated in the accompanying drawing, the essential elements of my invention being more particularly pointed out in the appended claims.

In the drawing, Figure 1 is a face or plan view of a post bar containing my invention; Fig. 2 is a side view of an associated pair of bars; Fig. 3 is a cross section of the bars on the line 3—3 of Fig. 2; Fig. 4 is a plan or face view of the locking mechanism within the casing member, the upper part of the casing being broken away to show the parts of the locking mechanism; Fig. 5 is a side view of the same, the post bar being shown in section and the parts of such mechanism being shown in locked position on the post; and Fig. 6 is a similar view, but with the parts in unlocked position.

The same reference characters indicate the same parts in all the figures of the drawing.

The post bars proper are formed each of a strip of sheet metal bent into the form of a flattened tube 1 continuous at one side with parallel contiguous flanges 2 extending outwardly from the center of one side of the tube. These flanges are formed with short retaining lugs 3 struck up from the body of the flange arranged to engage a slotted tube 4 which is slid over the pair of flanges and engages them tightly. The flanges are cut away transversely at suitable points (in the present instance at two points) to provide hinge openings for engagement with tubular hinging members 5 secured to the sides 6 of the binder. The number and exact formation of the retaining lugs 3 may vary, but in any case they should be sufficient in number to effectively prevent separation of the parts, and whether formed as a small protuberance, as shown, or as a severed bent-up tongue of metal, the size and disposition of the lugs is such as to cause a snug fit of the tube 4 against the opposite lugs and the edges of the flange members. A pair of lugs, severally arranged on opposite flange members on each side of a hinging member, with one or more intermediate lugs, may suitably be used to attain the desired connection of the parts. End caps 7 are secured to the post bars and tubes to provide a neat finish.

It will be understood that the posts 8 (which may and usually are of sectional construction) are rigidly secured to one post bar, as the lower one shown in Fig. 3, and pass loosely through orifices in the other bar. Within the latter are housed the novel duplicate locking mechanisms which I have devised for detachably securing the bar and attached cover to the posts. Describing now one of these locking mechanisms, the locking member consists of a rocking metal plate 9, having an orifice 10 slightly larger than the post 8 which engages it, and formed with a pair of legs 11 having at their lower ends lugs 12 which are seated in apertures in the bottom fold of the post bar, the positions referred to being those of the parts as illustrated in Figs. 5 and 6. Extending horizontally to the left is a lever arm 13 which is engaged by a push button 14 flanged within the post bar and having a lower convex engaging face 15. The left side of the plate 9 is formed with a stop 16 which when the push button is depressed to rock the plate forms a positive stop to prevent movement of the plate past a position in which the plate lies parallel with the sides of the post bar. The locking plate 9 is yieldingly maintained in the locking position shown in Fig. 5 by a spring 17 which is formed with a cross portion *a* engaging the upper inner face of the post bar at the left of the post, opposite branches *b* extending to the other side of the post, coils *c*, and end portions *d* which extend from the coils towards the right and are fastened to the plate by terminal bends which extend through orifices therein. This novel

construction of the spring member provides a very reliable and efficient spring action, superior in operation and less liable to disengagement than any form of spring used in other devices of this character that is known to me.

As will readily be understood from the foregoing description, the locking plate 10 grips the post bar firmly when in the oblique position shown in Fig. 5, whereas when the plate is shifted by actuation of the push button to the position shown in Fig. 6 (both buttons being simultaneously operated) the post is released. The rounded form of the 15 lower side of the push button permits it to have a rolling contact on the lever arm 13, and thus permits it to move freely in a direct line, without turning sidewise in its seat in the post bar.

20 I claim:

1. A post bar consisting of a strip of sheet metal folded to form a hollow flattened post bar proper and contiguous parallel flanges at one side thereof, and a slotted tube 25 extending over said flanges and secured thereto.

2. A post bar consisting of a strip of

sheet metal folded to form a hollow flattened post bar proper and contiguous parallel flanges at one side thereof, said flanges being formed with retaining lugs, and a slotted tube 30 extending over said flanges and engaging said retaining lugs.

3. A post bar consisting of a strip of sheet metal folded to form a hollow flattened post bar proper and contiguous parallel flanges at one side thereof and a slotted tube 35 extending over said flanges and secured thereto, said flanges being cut away at a plurality of points between said post bar proper and tube to form hinge openings.

4. In a hollow orificed post bar, a spring-pressed normally inclined orificed plate having legs seated at one side of the post orifice in the lower wall of the bar and also having on such side a lever arm and having on the opposite side a stop arm arranged to contact with the upper wall of the bar when the plate is shifted to position parallel with the walls of the bar, and a push 45 button having a flanged convex lower end 50 engaging said lever arm for rocking said plate.

WILLIAM J. STEENROD.
